PROCESS FOR THE PRODUCTION OF DI-AMINO-ALCOHOLS OF THE AROMATIC SERIES

Gustav Heilner, Berlin-Fichtengrund, Post Fried-
richsthal, Germany, assignor to Chemische
Fabriken Dr. Joachim Wiernik & Co., Aktien-
gesellschaft, Berlin-Waidmannslust, GermanyNo Drawing. Application January 26, 1934, Serial
No. 708,517. In Germany February 1, 1933

1 Claim. (Cl. 260—128.5)

The present invention relates to a process for the production of diamino-alcohols of the aromatic series of the type:

10 in which R_1 denotes an aromatic radicle, R_2 hydrogen or methyl, R_3 a diaminoalkyl radicle and

The invention can be carried out in numerous ways, the most important of which will be explained by the aid of equations.

1. If aliphatic aromatic halogen ketones, of the type $R-CO-CH(\text{halogen})X$ —in which R denotes an aromatic radicle and X hydrogen or methyl—be caused to react with a diamine having 1 nitrogen atom in tertiary combination, a diaminoketone is obtained. On reduction, this furnishes the desired diamino-alcohol, for example:—

30 R_4 hydrogen or a hydrocarbon radicle. The production of said diamino-alcohols is effected by treating aliphatic aromatic compounds, having one or two oxygen atoms in the side chain, with diamines in which 1 nitrogen atom is in tertiary, and the other in primary or secondary combination, the resulting reaction products being reduced if necessary.

35 40 The operations are performed in the manner customary for the production of the monoamino alcohols, such as ephedrin. According to the present invention however, the monoamines

a single working stage, by effecting the condensation in the presence of reducing agents

10 3. If fatty-aromatic oxy-oxo-compounds of the type $R-\text{CH}(\text{OH})-\text{CO}-\text{X}$ (in which R denotes an aromatic radicle and X hydrogen or methyl) be caused to react with diamines containing one nitrogen atom in tertiary, and the other in primary, 15 combination, water is split off and a condensation product is formed which, during subsequent reduction, furnishes the desired diamino-alcohol by accretion of hydrogen on the double linkage.

In this case also, the two working stages may be combined, if the condensation of the keto-alcohol with the diamine be effected in presence of reducing agents.

4. If a fatty - aromatic halogen - alcohol
 40 $R.CH(OH).CH(\text{halogen})X$ (in which R denotes an aromatic radicle, and X hydrogen or methyl) be caused to react with diamines containing 1 nitrogen atom in tertiary combination, the desired diamino-alcohol will be formed

45 In such case, however, it is preferable to start, not with halogen-alcohols, but with the corresponding ethers, the ether being subsequently split up.

The resulting products possess valuable therapeutic properties, and are intended for the treatment of asthma.

EXAMPLE 1

RACEMIC 1-PHENYL-2-(METHYL-(DIETHYLAMINO-ETHYL))-AMINOPROPANE-1-OL.

(1) 1-phenyl-2-(methyl-(diethylaminoethyl))-aminopropanone 5

A solution of 21.3 grams of α -bromopropiophenone in 50 cc. of ether is treated with 26 grams of α -methylamine- β -diethylaminoethane, accompanied by cooling. The precipitation of α -methylamino- β -diethylaminoethane-hydrobromide commences after a short time. After leaving the mixture at rest for several hours in the cold, the reaction is completed by gentle heating. The precipitated salt is separated by filtration, and the oily residue is distilled in vacuo. Under a pressure of about 1 mm. the 1-phenyl-2-(methyl-(diethyl-

aminoethyl))-aminopropanone passes over at 132-134° C., as a yellowish oil, which darkens on being left exposed in the air. The yield of pure product is 21 grams (i. e. about 80% of theory). 20

(2) *Racemic 1-phenyl-2-(methyl-(diethylaminoethyl))-aminopropane-1-ol*

A solution of 13.1 grams of the keto-base, (obtained as in 1), in the calculated quantity of dilute aqueous hydrochloric acid, is treated with 25 grams of a palladium and barium sulphate catalyst, containing 0.5 grams of metallic palladium, and agitated in presence of hydrogen. After the calculated amount of hydrogen has been absorbed, the catalyst is filtered off and the reduc-

tion product is set free by addition of alkali. Under a pressure of 1.5-2 mm., the racemic 1-phenyl-2-(methyl-(diethylaminoethyl))-amino-

propane-1-ol boils at 140-141° C. An almost theoretical yield is obtained. The dihydrochloride obtained by precipitating the ethereal solution of the base with ethereal hydrochloric acid, is a hygroscopic crystalline mass. Analysis showed 20.8 of chlorine (theory 21.04% Cl).

EXAMPLE 2

- (1) *p*-Methoxy- ω -(methyl-(diethylaminoethyl))-AMINOETHYL)-AMINOETHANE-1-OL
 (1) *p*-methoxy- ω -(methyl-(diethylaminoethyl))-aminoacetophenone

18.5 grams of *p*-methoxy- ω -chloracetophenone (Ber. deutsch. chem. Ges., 30 (1897), p. 1715) are distributed in 50 cc. of benzene and gradually treated with 26 grams of α -methylamino- β -diethylaminoethane. Spontaneous heating, tempered by intermittent cooling, occurs, the halogen-ketone passing into solution, whilst α -methylamino- β -diethylaminoethane hydrochloride is precipitated. After standing for several hours at room temperature, followed by a brief moderate heating, the reaction mixture is agitated with water, whereupon the precipitated salt redissolves. The benzene solution is freed from the solvent in vacuo, the residue is taken up with acetone and treated with ethereal hydrochloric acid until the reaction solution is acid to Congo solution as indicator. The dihydrochloride of the methoxy- ω -(methyl-diethylaminoethyl)-aminoacetophenone thereupon separates as a rapidly solidifying oil. The salt is very sparingly soluble in acetone. It is crystallized from a mixture of acetone with a small amount of alcohol, and melts, with decomposition, at 170-171° C. Yield: 25 grams of dihydrochloride (71% of the theoretical).

- (2) 1-(methoxyphenyl)-2-(methyl-(diethylaminoethyl))-aminoethane-1-ol

20 grams of the dihydrochloride obtained in 1, are dissolved in water and agitated with hydrogen, under a slight positive pressure, in presence of palladinized charcoal. After the theoretical amount of hydrogen has been absorbed, the catalyst is filtered off, the liquid being rendered alkaline and extracted with ether, and the extraction residue distilled in vacuo. The 1-(*p*-methoxyphenyl)-2-(methyl-(diethylaminoethyl))-aminoethane-1-ol passes over at 185-190° C. (pressure 5 mm.). The dihydrochloride melts at 158-160° C.

EXAMPLE 3

1-PHENYL-2-(DIETHYLAMINOETHYL)-AMINOPRO- PANE-1-OL

23.2 grams of 1-amino-2-diethylaminoethane (Berichte, 29, p. 2526) in 100 cc. of methyl alcohol are mixed with a solution of 6.4 grams of sulphurous acid in 150 cc. of methyl alcohol, 20 grams of zinc dust being added and the whole actively stirred. The mixture is heated to boiling, under a reflux condenser. In the course of about 2 hours, 20 grams of phenylpropandione, dissolved in 100 cc. of methanol, are dropped in, 11 grams of sulphurous acid in 170 cc. of water, and a further 20 grams of zinc dust being added at the same time.

When reduction is complete, the liquid is filtered and acidified, the methanol being distilled off and the solution repeatedly extracted with ether in order to remove non-basic constituents. After the solution has been rendered alkaline, the new base is taken up with ether and fractionated under a good vacuum. Under a pres-

sure of about 0.5-1 mm. the racemic 1-phenyl-2-(diethylaminoethyl)-aminopropane-1-ol passes over at about 140° C. For further purification it is taken up with alcohol and treated with alcoholic oxalic acid, the very sparingly soluble oxalate (melting point 180-182° C.) being precipitated. In order to prepare the dihydroiodide, the free base is regenerated from the oxalate by means of alkali, then neutralized with hydriodic acid, brought to dryness and recrystallized from isopropyl alcohol. It melts at 176-178° C.

EXAMPLE 4

1-PHENYL-2-(DIETHYLAMINOETHYL)-AMINO- PROPANE-1-OL

15 grams of phenylpropanolone in 30 cc. of ether are treated with 12 grams of 1-amino-2-diethylaminoethane, and the whole is warmed under the reflux condenser for a short time. A condensation product with the character of an azomethine is formed, which can be subjected to reduction without further purification. After addition of palladium catalyst, the ethereal solution is agitated with hydrogen under pressure until the calculated amount of hydrogen has been absorbed. The reduction is then stopped, the catalyst filtered off, and the solution rendered alkaline in order to remove non-basic constituents. The further treatment is performed in the same manner as set forth in Example 3.

EXAMPLE 5

1-PHENYL-2-(METHYL-(DIETHYLAMINOETHYL))- AMINOPROPANE-1-OL

23 grams of 1-phenyl-1-methoxy-2-bromopropane (Berichte, 58 (1925) pp. 1260-1270) and 26 grams of 1-methylamino-2-diethylaminoethane are left in contact for a short time, being then gradually heated and maintained for several hours at 100° C. The reaction mixture is diluted with ether, separated from the precipitated 1-methylamino-2-diethylamino-ethane hydrobromide, and the ether is distilled off. The residue is taken up with dilute hydrochloric acid, the aqueous acid solution is extracted with ether, to remove non-basic constituents, and after being rendered strongly alkaline with caustic potash, is again repeatedly extracted with ether. After the ether has been distilled off, the liquid is heated at 100° C. for 1 hour with a threefold quantity of hydrobromic acid saturated at 0° C. When the liquid has cooled down, it is rendered alkaline, and the liberated base is fractionated in vacuo. The constituent passing over at 130-135° C., under a pressure of about 1 mm., represents the desired racemic 1-phenyl-2-(methyl-(diethylaminoethyl))-aminopropane-1-ol.

What I claim and desire to secure by Letters Patent of the United States is:

The process which consists in causing fatty-
aromatic halogen ketones of the type:

in which R denotes one element of the group consisting of phenyl and mono methoxy phenyl, X one element of the group consisting of hydrogen and methyl, to react with

wherein R_5 represents one element of the group consisting of hydrogen and methyl and subjecting the diamino-ketones thus obtained to a reduction.

GUSTAV HEILNER. 75
